Edgar Ellsworth Phinney, West Orange, N. J.,
assignor to Defiance Manufacturing Corporation,
Orange, N. J., a corporation of New York

Application August 24, 1935, Serial No. 37,648

7 Claims. (Cl. 101—93)

The invention has relation to checkwriters, and more particularly to value selecting mechanism for such machines.

The invention is designed to provide novel means for bringing type representing various numeral values to the printing line according to the values set up on digit keys of a keyboard. A further feature of the invention is the novel arrangement of the digit figures and symbols on the type bars.

Suitable means for printing foreign currency designations are also provided.

The invention consists in the novel construction and combination of parts as set forth in the appended claims.

In the accompanying drawings illustrating the invention,

Fig. 1 is a right hand elevation of the machine showing the clutch control means, the casing being removed.

Fig. 2 is a cross sectional view taken substantially on line 2—2 of Fig. 6, and showing the type slide operating means.

Fig. 3 is a transverse cross section taken on line 3—3 of Fig. 2 showing keyboard control means.

Fig. 4 is a right hand elevation taken inside the right hand framing of the machine.

Fig. 5 is a detail of the check operated control switch.

Fig. 6 is a plan view, the keyboard being removed.

Fig. 7 is a plan view of the machine operating and drive means.

Fig. 8 is a front elevation, the casing having been removed.

Fig. 9 is a detail of the British pounds type slide.

Fig. 10 is a bottom view of the type slides and the currency change plate.

Type selecting mechanism

The keyboard mechanism is of well known type, such, for instance, as described in Patent #1,399,-652, granted to Edgar E. Phinney on December 6, 1921, wherein any of the digit keys 1 upon depression, are held in depressed position until near the end of a cycle of operation by engagement of a notch 2 with suitable rocking bails 3. Near the end of a cycle of operation, the bails 3 will be rocked to release the keys 1 by movement of transverse slide 4, as will hereinafter be described.

As shown in Figs. 2, 3 and 6, there is provided for each order of digit keys 1 a plate 5, forming part of a type bar and slidably mounted upon guide frames 6 supported at their forward and

rearward ends upon transverse rods 7 secured to the framing of the machine. Each of the slide plates 5 is provided with type 8 bearing numerals and symbols, as indicated in Figs. 2 and 10, adapted to be brought to the printing line in the following manner. Plates 5 are each provided with a projection 9 adapted to cooperate with any of the depressed digit keys from 1 to 4 of the related column, and a projection 10 adapted to cooperate with the depressed digit keys 5 to 9, the keys acting as stops, to limit rearward movement of the related plates 5. As indicated in Fig. 2, by arranging the projection 9 of slide 5, normally a full step of movement in front of digit key 1 and the projection 10 of said slide a half step of movement in front of digit key 5 and by alternating the figures of the series 1-4 and 5-9 on the type bar, it is possible to reduce the total movement of slide plate 5 to approximately one half the total digit key spacing. Also by allowing the full extent of movement of the slide 5, that is until the surface 11, thereof engages frame 12, to bring the zero type to the printing line, the star type may be placed in the usual normal zero position, thus it is possible to have eleven characters on the type bar, adapted to be controlled according to the setting of but nine digit keys, as will more fully be described.

Pivotedly mounted at 13 and extending longitudinally beneath each column of digit keys 1 are arms 14, each of said arms being provided with a projection 15, lying in the path of projection 16 of the related slide plate 5 and forming a latch, so that the plates are held in normal position in any columns in which no keys have been depressed. Depression of a digit key will, however, rock arm 14 of the corresponding order downwardly, moving projection 15 downwardly out of the path of movement of projection 16, whereupon slide 5 will be free to move rearwardly to a position determined by the depressed key.

Manual operating means

All of the slide plates 5 are normally held in their forward positions by means of a restoring bar 17, slidably mounted upon guide frame 18 and extending transversely across the rearward end of slides 5. Bar 17 is urged forwardly under influence of its spring 19, secured at 20 to the forward arm of said bar, the forward movement being limited by engagement of projection 21 with the transverse frame 12 (Figs. 2 and 6).

The operator having placed a check in printing position, between the guides 22 (Fig. 1), and having set up the amount desired on the keyboard,

depresses operating key 23 to initiate a printing cycle of operation, as follows:

Pivotedly mounted up on the framing at 24 is a latch plate 25 normally holding the clutch pawl 26 (pivoted at 27 upon disc 28, fast to shaft 29) out of engagement with the teeth of notched disc 30. Notched disc 30 is loosely mounted upon shaft 29 and has drive connections with the motor, through gears 31, 32, 33, 34 and 35. Plate 25 is normally held engaged with pawl 26, against tension of spring 36, by engagement of latch arm 37 (pivotedly mounted at 38 to latch 25) with rod 39 extending through the right hand frame of the machine.

Upon depression of key 23, pawl 40 pivotedly mounted at 41 upon a rearwardly extending arm of said key and having engagement with a projection 42 of latch arm 37 will rock said latch free of rod 39, whereupon plate 25, under influence of spring 36 will be rocked counterclockwise as seen in Fig. 1 releasing pawl 26, and allowing said pawl under influence of its spring 43 to engage notched disc 30.

Fast to latch plate 25 is a pin 44 extending laterally through an orifice 45 of a switch operating arm 46 (Fig. 4) slidably mounted upon stud 47 of the frame. During the above described movement of latch plate 25, pin 44 will move arm 46 rearwardly causing the insulated roller 48, mounted thereon to close the contacts 49 of the motor switch 50 to start the motor and impart, through the previously described gear train, a clockwise rotative movement to the notched disc 30 and, through engagement of pawl 26 with said disc, the plate 28 and shaft 29.

Secured to the shaft 29 is a cam 51 (Figs. 2 and 7) adapted by cooperation with a roller 52 to impart clockwise movement to an oscillating arm 53, pivotally mounted at 54 upon a support member 55. Oscillating arm 53 has connection, through link 56 and flexible chain 57, with the restoring frame 17 as shown in Figs. 2 and 6, so that rotation of cam 51, will pull restoring frame 17 rearwardly against tension of spring 19.

Each of the type bar slides 5 has yieldable spring connection 58 with the frame 17, and as said frame is drawn rearwardly, slide plates 5, (in those columns wherein a key has been depressed) under influence of said springs, will be caused to move rearwardly until stopped by engagement of the projection 9 or projection 10 with the related depressed key, thus bringing the corresponding value type to the printing line. In those columns to the left of the highest order digit key which has been depressed, projection 16 of slides 5 will contact projection 15 of arms 14 preventing movement of the higher order slides 5 and holding the stars in position at the printing line.

In order to bring the zero type into printing position in those columns to the right of the lowest order digit key which has been depressed, arms 14 are provided with projections 59, (Figs. 2 and 3) overlapping each the next lower order arm. There are no arms 14 provided in the units of dollars column or in the cents value columns, there being no star type for these columns. The type bars in these columns always move to the zero position if no key is depressed.

During the time roller 52 rides the concentric dwell of the high point of cam 51, cam 60, secured to shaft 29, will rock the platen 61 against the type, to print the desired value. Near the end of the cycle of operation roller 52 is allowed to move to the low portion of cam 51, releasing arm 53, whereupon spring 19 will return frames 17 to

their forward position, restoring the type bar plates 5 to normal position.

The printing operation having been completed, a pin 62 (Fig. 4), fast to a cam plate 63, rotatable with shaft 29, will engage and rock a lever 64 downwardly about its fulcrum 65 to retract the projection 66 of an arm 91 beneath the level of check support plate 67, thus freeing the check, whereupon said check, under influence of roller 68, having suitable drive connections with the 10 motor, will be ejected from the machine.

Near the end of the cycle of operation, pin 62 will engage surface 69 of a lever 70, fulcrumed at 71, and rock said lever clockwise as viewed in Fig. 4. Upon clockwise movement of lever 70, 15 roller 72, mounted upon the forward end thereof, will engage lever 73, rocking said lever counterclockwise about fulcrum 74, thus rocking lever 75 to provide lateral displacement of clearing slide 4 (Fig. 3), by means of a bell crank lever similar 20 to that described in Patent #1,432,616, issued to Edgar E. Phinney on October 17, 1922. Suitable repeat key mechanism is provided, adapted to render lever 75 inoperative, also a clear out key, as fully set forth in the above-mentioned patent. 25

Keyboard locking means is provided comprising the cam plate 63, adapted by cooperation with roller 76 of arm 77 to rock shaft 71 clockwise. Secured to the left hand end of shaft 71 (Figs. 2, 3 and 7) is an arm 78 provided with an embossed portion 79 adapted by the above described movement of said arm to be brought into relation with locking slide 80, thus preventing lateral movement of said slide. Slide 80 is provided with projections 81, cooperating with key locking 35 bails 3 to lock keys 1 in raised position.

Near the end of a cycle of operation pivot stud 27 (Fig. 1) of disc 28 engages projection 82 of latch plate 25, restoring said plate to normal position and bringing the projection 83 thereof into 40 the path of movement of pawl 26 to disengage said pawl from the driving member 30. Restoring of latch plate 25 carries latch arm 37 forwardly, said arm under influence of its spring 84 rocking about point 38, returning to its normal position 45 behind rod 39 and into engagement with pawl 40.

During the excursion of frame 17, a roller 101 mounted thereon will operate the usual ribbon feed mechanism.

Automatic check controlled operating means 50

While the manually operated key 23 is provided to be used if desired, an operating cycle of the machine is normally initiated by insertion of the check into the machine.

For key control operation the projection 85 (Fig. 5) of slide 86 is adjusted to a position opposite projection 66 of arm 91, so that said arm cannot rock laterally when a check is inserted from the left hand side of the machine. For 60 check control operation, however, slide 86, is manually set to the position shown in Fig. 5, wherein projection 85 is moved forward of projection 66. As a check is inserted into printing position between the guides 22 and beneath roller 68 the forward edge of the check engages projection 66 and rocks arm 91 to cause insulated roller 87, mounted on said arm, to engage contacts 88 of switch 89, said switch constituting circuit means to a solenoid 90 (Figs. 1 and 7). Engagement of contacts 88 of switch 89 will cause solenoid 90 to become energized, withdrawing the plunger rod 39 laterally away from latch arm 37, releasing said latch and thus the latch plate 25, allowing said plate under influence of its spring 75

36 to release clutch pawl 26, initiating the printing cycle in the manner previously described. During that portion of the cycle, following the printing action, the pin 62 in contacting arm 64 5 rocks said arm and, through projection 93, the arm 91 downwardly about its pivot point 94, releasing the check, said check being ejected by action of roller 68 as was previously described.

Foreign currency type plate

10 As shown in Fig. 10 a type plate 95, slidably mounted in the frame 12, is adapted to be moved longitudinally by means of thumb lever 96 to bring one of the series of word type opposite the printing line, plate 95 being held in set position by means of spring plunger 97 engaging one of the series of notches 98 of the guide rod 99. The word type plate bears the usual notations "Not over", "Dollars", "Cents" for United States 15 currency and the correspondingly terminology for foreign currency in other longitudinal positions. With the exception of the British currency system, the order of the type relative to plate 95 is immaterial. The British currency type 20 is, however, as shown in Fig. 10, placed in the rearward position relative to plate 95. This is necessary to provide for a 12th character, namely the British currency pounds symbol, to be placed upon the type bar in the third right hand order 25 column. The pounds symbol is adapted to be brought into printing position as plate 95 is moved to British currency position in the following manner:

As the plate 95 is moved to its extreme forward position, bringing the British currency 30 plate into printing line, the forward end 100 of guide rod 99 will engage the surface of projection 101 of a compound lever 102, fulcrumed on transfer shaft 103, rocking said lever counter-clockwise as viewed in Fig. 9. Secured to the type 35 plate 105 related to the third right hand column, is a pin 104 and as lever 102 is rocked, as above described, the surface 106 of said lever will engage pin 104 camming slide 105 forwardly, bringing the 40 pound symbol into printing position.

45 I claim:

1. In a checkwriter, the combination with a row of depressible digit keys, of a type bar extending beneath said keys and provided with two 50 projections each adapted to contact with any depressed one of a series of keys of said row, said projections being so spaced as to register alternately with keys of the one and the other series as said slide moves from one extreme adjusted position to the other, a row of digit type 55 spaced on said bar at intervals of half the extent of the intervals between the digit keys, and means for moving said type bar into contact with a depressed key.

60 2. In a checkwriter, the combination with a row of depressible digit keys, said row representing digits of uniformly progressive value, of a type bar extending beneath said keys and provided with two projections each adapted to contact with any 65 depressed one of a series of keys of said row, said projections being so spaced as to register alternately with keys of the one and the other series as said slide moves from one extreme adjusted position to the other, a row of digit type 70 on said bar, alternate type of the row representing digits of uniformly progressive value, and means for moving said type bar into contact with a depressed key.

75 3. In a checkwriter, the combination with a row of depressible digit keys, a type bar including

means slidable beneath said keys and adapted to contact with any depressed key of said row, whereby said bar is differentially located, and a row of digit type on said bar; of a non-value symbol type located on said bar at one end of the 5 row of digit type, a zero type located on said bar at the opposite end of said row, means for holding the type bar in adjustment with the symbol type at the printing line, a fixed stop for the bar adapted to locate the zero type at 10 the printing line, and means for releasing said type bar and moving it to effect contact with a depressed digit key or alternatively with said fixed stop.

4. In a checkwriter, the combination with ordinal rows of depressible digit keys, type bars including means slidable beneath the keys of each row and adapted to contact with any depressed key of said row, whereby said bar is differentially located, and a row of digit type 20 on each said bar; of non-value symbol type located on said bars at one end of the row of digit type, zero type located on said bars at the opposite end of said row, fixed stops adapted to locate the zero type at the printing line, springs 25 adapted to move said type bar against said stop, latches adapted to hold the non-value type at the printing line, against the tension of said springs, said latches being each displaceable by a depressed key, and offset lugs on said latches, over- 30 lying each and adapted to displace the latch of lower order.

5. In a checkwriter, the combination with a row of depressible digit keys, a type bar including 35 means slidable beneath said keys and adapted to contact with any depressed key of said row, whereby said bar is differentially located, a row of digit type on said bar, a spring adapted to move said type bar into contact with a depressed key, and a latch adapted to hold the bar against 40 the tension of said spring; of a non-value symbol type on said bar, and means manually settable to adjust said type bar away from the latch and against the tension of its spring and to hold the 45 symbol type at the printing line.

6. In a checkwriter, the combination with ordinal rows of depressible digit keys, type bars including means slidable beneath the keys of each row and adapted to contact with any depressed key of said row, whereby said bar is differentially located, a row of digit type on each said bar, means for holding each type bar as located, and means operable to release and relocate all of said bars simultaneously; of a type 55 plate provided with rows of non-value type, separated by certain of said type bars, and means manually settable to adjust said type plate and to hold selected non-value type at the printing line, independently of the releasing means.

7. In a checkwriter, the combination with ordinal rows of depressible digit keys, type bars including means slidable beneath the keys of each row and adapted to contact with any depressed key of said row, whereby said bar is differentially located, and a row of digit type on each said bar; of a non-value symbol type on one of said bars, a type plate provided with rows of non-value type, and means manually settable to adjust said type plate and to hold selected non-value type at the printing line, including an element adapted, upon movement of said plate to one extreme position of adjustment, to move and hold the symbol type at the printing line.
